WEFT EXHAUSTION INDICATING APPARATUS

Edward J. Abbott, Wilton, N. H., assignor to
 Abbott Machine Company, Wilton, N. H., a corporation of New Hampshire

Application July 12, 1939, Serial No. 284,011

3 Claims. (Cl. 139—205)

This invention relates to looms and more particularly to mechanism for detecting the exhaustion of the filling yarn in the shuttle and for controlling any part of the loom in accordance with the detection of such exhaustion.

The invention involves in its preferred form an improved form of shuttle, an improved form of shuttle bobbin, the shuttle and bobbin cooperating to close a partial electric circuit within the shuttle upon the exhaustion of the yarn, and an improved form of means adapted to cooperate with the shuttle to connect the partial electric circuit of the shuttle with the remainder of an electric circuit adapted to respond to the detection of exhaustion.

The principal objects of the invention are to provide a more reliable closure of the partial electric circuit within the shuttle upon the occurrence of exhaustion; to provide simplified electrical connections within the shuttle and shuttle bobbin; and to provide improved and more reliable contacting mechanism on the shuttle and at the shuttle boxes to connect the partial electric circuit of the shuttle with the remainder of the loom controlling circuit. A further object of the invention is to provide a yarn-contacting circuit-closing element so constructed and arranged with relation to the yarn on the bobbin as to contact the endmost turns of yarn on the bobbin and adapted to allow these turns to be unwound without any possibility of their catching on the yarn-contacting element.

Other objects of invention and features of advantage and utility will be apparent from this specification and its drawings wherein the invention is explained by way of example.

In the drawings:

Fig. 1 is a side elevation of a typical loom with the shuttle contact plates of the present invention applied thereto;

Fig. 2 is a plan view with a portion thereof in horizontal section showing the right hand end of the shuttle of Fig. 1;

Fig. 3 is a vertical section on the line 3—3 of Fig. 2;

Fig. 4 is a side elevation of a portion of the shuttle shown in Fig. 2;

Fig. 5 is a sectional view taken through the longitudinal axis of the shuttle bobbin;

Fig. 6 is a vertical section on the line 6—6 of Fig. 2, but showing the shuttle bobbin as in a condition of substantial exhaustion and showing the yarn-contacting element of the shuttle in its exhaustion detecting position;

Fig. 7 is a front diagrammatic view of the right hand shifting shuttle box of a 4 x 4 loom with parts broken away to show a shuttle entering the upper box; and

Fig. 8 is a diagrammatic plan view of the mechanism of Fig. 7.

The shuttle shown in the drawings and indicated generally by the reference character 11 is provided with a resilient bobbin-holding yoke 12 and a shuttle bobbin indicated generally by the reference character 13, both of the type employed in automatic looms, the bobbin having its enlarged wooden base 14 provided with three metallic rings 15 adapted to engage corresponding recesses in the yoke 12. A guide plate 17 is provided as is customary in shuttles of this type to assist in positioning the base of the bobbin in the yoke.

Referring now to Fig. 6, the yarn Y wound on the bobbin has a small reserve or bunch sufficient in amount to supply one or a few picks of the shuttle before the bobbin becomes absolutely bare. As illustrated in Fig. 6, this reserve takes the form of three small connected windings 18, 19 and 20, the last of these (or the first to be wound on the bobbin) terminating a short distance from the enlarged base 14 of the bobbin. It will be understood that in winding the bobbin, after winding whatever reserve is required, the yarn is then carried completely over to the enlarged base 14 and traversed with a progressively shifting traverse so that the barrel of the bobbin is covered nearly to its outer tip, Fig. 2 showing a typical shape of the right-hand part of the body of yarn on the full bobbin.

As shown in Figs. 5 and 6, the barrel 25 of the spindle is encircled with a thin metallic ferrule 26 abutting the enlarged head portion 14, a part of the ferrule 26 being exposed when all of the yarn except that constituting the small reserve has been unwound. A yarn-contacting element in the form of a metal spiral spring 28 is fastened at its opposite ends in the sides of the shuttle so that it presses inwardly and somewhat forwardly against the endmost turns of yarn on the wound bobbin abutting the enlarged head 14. The left end of the spring 28 as shown in Fig. 3 is secured to one side wall of the shuttle by a screw 30 of which the threads interfit with the coils of the spring. The opposite end of the spring has its end portion of wire straightened out and engaged under a contact plate 35 which clamps it against the side wall of the shuttle. As shown in Fig. 3, the coil spring 28 is deflected by the yarn of an unexhausted bob-

bin, but as shown in Fig. 6 comes into contact with the ferrule 26 upon substantial exhaustion of the yarn.

The ferrule 26 is connected by a wire 38 with one of the metal rings 15 encircling the enlarged base 14. In addition to the contact plate 36, the shuttle is equipped with a similar contact plate 35 which, as indicated in Fig. 2, is connected by a wire 40 with the transverse pin 41 that retains the yoke 12 in position.

By this arrangement of electrical connections the contact plates 35 and 36 are electrically connected when the yarn has exhausted to the condition of Fig. 6 and form a partial electrical circuit comprised of the contact plate 35, spring 38, ferrule 26, wire 38, one of the rings 15, yoke 12, pin 41, wire 40 and contact plate 36. Before the yarn has been unwound to the condition shown in Fig. 6, this partial circuit is kept open by the fact that the yarn-contacting spring 28 is held out of contact with the ferrule 26.

By the location and construction of the yarn-contacting coil spring 28, the yarn is enabled to be unwound readily without any danger of catching on this spring. The yarn unwinding from the bobbin shown in Fig. 2 is withdrawn altogether toward the left, and the spring 28 pressing against the inclined face of the yarn mass abutting the enlarged head 14 does not obstruct the unwinding.

Referring to Figs. 7 and 8 where the vertically shifting shuttle boxes at one end of the loom are diagrammatically shown, each shifting shuttle box is equipped with the usual binder 50 pivoted at 51 and spring-pressed to receive and retain the entering shuttle. On the binder for each shuttle box, near the pivot 51 there is provided a vertical block of insulating material 52 slotted at 53 and 54. A wire 56 of spring material extends from a binding post 57 horizontally over to the block 52 and there is bent horizontally so as to extend through the slot in the block to the rear face of the block. At this point the wire 56 is bent into a horizontal loop 58, lying in a plane parallel with the path of the shuttle. Each shuttle box is equipped with two such wires 56 and their loops 58 are positioned so that their edges make contact with the shuttle contact plates 35 and 36 when the shuttle is retained in the shuttle box by the binder.

Referring to Figs. 1, 4 and 7, each of the shuttle contact plates 35 and 36 is provided with vertical corrugations, that is, corrugations extending perpendicular to the path of travel of the shuttle and perpendicular to the planes of the wire loops 58. The corrugations on these plates and the small area but firm nature of the contact afforded by the spring-pressed loops 58 afford a definite reliable electrical contact quite unaffected by the tendency of such contact elements to acquire a gummy coating when used in a loom. Gum cannot accumulate in any definite spot on the surface of the contact plates 35 and 36 relied upon for contact, because it is scraped into the recesses of the corrugations. Likewise gum is unable to accumulate on the portion of the loop 58 relied upon for contact because the travel of the corrugated plates over the loop continually keeps the contacting surface of the loop clean.

Referring to Fig. 7 one of the two binding posts 57 of each shuttle box is grounded to the frame of the machine while the remaining binding

posts of the group of shuttle boxes are connected with L-shaped contact plates 60, 61, 62 and 63 respectively. As the shuttle boxes shift up and down these L-shaped contact plates make contact with a stationary spring contact 66 which is connected by a wire 67 to whatever control mechanism is to be actuated by the detection of exhaustion, the other side of the control circuit being grounded to the frame of the machine. In 10 this way initiation of the action of the control mechanism is determined by the condition of the bobbin in the shuttle of whatever shuttle box has its L-shaped contact member in contact with the stationary spring contact 66. Preferably, 15 the stationary spring contact 66 is so positioned that it contacts with the L-shaped contact of whatever shuttle box is in the picking position, so that the loom is controlled by the particular shuttle that is about to make a pick.

As examples of control mechanism which the electrical circuit of the present invention in its broader aspects is suitable to operate, there may be cited; mechanism for stopping the loom, mechanism for changing shuttles, and mechanism for replenishing exhausted shuttles with new bobbins. In the form illustrated in the present application, the loom control mechanism is a loom brake, the functions of changing shuttles and replenishing bobbins being performed 30 manually.

I claim:

1. A shuttle having therein two side portions with a space therebetween for a bobbin, means for holding a bobbin in said space, a coil wire 35 spring extending across said space in position to contact with and be deflected laterally by a winding of yarn on the bobbin, the coil wire spring being adapted upon exhaustion of the said 40 yarn to press laterally against an electrically conducting portion of the bobbin, and electric contacts on the shuttle connected to said spring and said bobbin-holding means respectively.

2. A shuttle having therein two side portions with a space therebetween for a bobbin, means for holding a bobbin in said space, a coil wire 45 spring extending across said space in position to contact with and be deflected laterally by a winding of yarn on the bobbin, the coil wire spring being adapted upon exhaustion of the said 50 yarn to press laterally against an electrically conducting portion of the bobbin, and electric contacts on the shuttle, one end of the wire of the spring being clamped against the shuttle by one of said contacts, and the other of said contacts being connected to said bobbin-holding means.

3. A shuttle having therein two side portions with a space therebetween for a bobbin, means for holding a bobbin in said space, a coil wire 55 spring extending across said space in position to contact with and be deflected laterally by a winding of yarn on the bobbin, the coil wire spring being adapted upon exhaustion of the said 60 yarn to press laterally against an electrically conducting portion of the bobbin, and electric contacts on the shuttle, one of said contacts being connected to said bobbin-holding means, the other of said contacts being connected to one end of the coil wire spring, and a screw engaging a 65 side portion of the shuttle and having threads interfitting with coils of the opposite end of said spring to hold the same.

EDWARD J. ABBOTT.
